United States Patent Office

Des. 195,088

Patented Apr. 23, 1963

195,088

FOOTBALL KICKING TEE

Vester R. Box, 3549 Bryn Mawr Drive, Dallas, Tex.

Filed Aug. 15, 1962, Ser. No. 71,291

Term of patent 14 years

(Cl. D34—5)

FIG. 1 is a top plan view of a kicking tee, showing my new design;

FIG. 2 is a rear elevational view thereof; and

FIG. 3 is a longitudinal cross section as indicated by III in FIG. 2.

I claim:

The ornamental design for a football kicking tee, as shown.

References Cited in the file of this patent

UNITED STATES PATENTS

D. 150,195 Barton ----- July 13, 1948

OTHER REFERENCES

MacGregor Sports Equipment, Fall and Winter, 1953, page 41, item F690, Staley Kicking Tee.

Montgomery Ward, 1961 Christmas Catalog, page 179, upper right illustration, No. 2, Football Kicking Tee.